J. F. SMITH.
ROTARY PUMP.
APPLICATION FILED MAR. 5, 1921.

1,417,418.

Patented May 23, 1922.

John F. Smith,
By Hiram Swartz, City.

UNITED STATES PATENT OFFICE.

JOHN F. SMITH, OF WOOSTER, OHIO, ASSIGNOR OF ONE-HALF TO CHARLES M. JEFFRIES,
OF APPLE CREEK, OHIO.

ROTARY PUMP.

1,417,418.

Specification of Letters Patent. Patented May 23, 1922.

Application filed March 5, 1921. Serial No. 449,997.

To all whom it may concern:

Be it known that I, JOHN F. SMITH, a citizen of the United States, residing at Wooster, in the county of Wayne and State 5 of Ohio, have invented a new and useful Rotary Pump, of which the following is a specification.

My invention relates to improvements in rotary pumps or engines, and particularly 10 to improvements upon my former invention for like use set forth in Letters Patent of the United States, No. 1,045,754, issued thereon to me November 26, 1912, the main object of which was to provide means for keeping the piston automatically in tight engagement with the cylinder wall of the pump at all 15 times, irrespective of wear, and means for holding the piston on its seat in such manner as to take up its own wear automatically.

20 The main object of my present invention is to combine with said means a simple and practical device for largely increasing the pumping capacity and for making the pump cylinder a stationary valve within itself, without the aid of any other valves or valve 25 connections heretofore required, and, secondly, to so construct the cylinder and its connections as to avoid the use of bolts, and provide means for threading the several 30 parts of the mechanism together compactly so as to simplify its manufacture and increase its durability and efficiency.

My invention consists principally of the 35 novel construction of the pump cylinder by coring out the walls thereof in such manner as to form cavities therein for the passage of water therethrough, and to so divide said cavities as to cause both suction and discharge 40 of the water by the revolving eccentric piston within the cylinder with each revolution of said piston; and it further consists in providing enlarged and more numerous openings into said cavities for the inflow and discharge of water, thereby largely increasing 45 the capacity of the pump, and the incidental features as hereinafter fully set forth, and stated in the appended claims.

50 My invention is illustrated by the accompanying drawings in which similar letters and figures of reference indicate like parts.

Referring thereto, Fig. 1 is a vertical longitudinal section through the pump casing. Fig. 2 is a side view of the pump body, one 55 side being cut away for better illustration of the interior; and Fig. 3 is a horizontal sec-

tion taken on the dotted line 2—2 of Fig. 1, and Fig. 4 is a detailed vertical elevation of the rotor, detached. Fig. 5 is a horizontal cross section of Fig. 2 on the dotted line 3—3.

In the drawings, A represents the cylinder 60 casing of the pump, having a conical well therein as heretofore, and an eccentrically disposed conical socket j at its base J, and a conical opening through its top N adapted to receive the collar I and stud H about 65 which it is threaded, as shown in Fig. 1.

The members N and J are preferably inserted separately from the cylinder and secured thereto by set screws t and g, respectively. Said top N is also perforated with 70 a plurality of openings through which water is discharged upwardly from the cavity in the cylinder, as shown by the arrows a a a a.

The walls of said cylinder are cored out to 75 form cavities K K' therein, which, on one side of the cylinder, open upwardly for the escape of water discharged therethrough in the direction of said arrows, and on the other side of said cylinder the cavities open downwardly through the walls, and, by suction 80 therethrough, the water passes upwardly into and through said cavity in the direction of the arrows a' a'. The said cavities are divided on one side of the cylinder by a vertical diaphragm M (best shown in Fig. 85 2), and also by a spiral diaphragm L, whereby the water below the cylinder is drawn upwardly by suction through said openings a' a', and are discharged upwardly through 90 said openings a a a into the pipe chamber F, and thence into the pump pipe P, by the 95 action of the rotor B within the chamber of the cylinder, as hereafter more fully described. The tubular caps E and F are respectively connected to the top and bottom 100 of the cylinder body A by the threaded connections shown in Fig. 1, and to the well pipes P and P' by similar threaded joints, so as to make the same air tight and impervious to water; the construction of the cylinder body being such as to admit of such connection, and obviate the use of bolts as heretofore employed, thus adapting the exterior 105 of said body to fit within an outer casing, such as is commonly used in deep wells, but not herein shown because immaterial except incidentally. A plurality of openings O O' along each side of the vertical diaphragm M afford channels for suction of the water on one side of the latter, and discharge thereof 110

on the other. To cause this action of the water the rotor B, having a frusto-conical body, and eccentrically disposed within the cylinder, as heretofore, is provided with a 5 single flat member C, which is loosely mounted to slide laterally through a slot f, (Fig. 3) therein, freely, in such manner as to vibrate back and forth therein with its opposite ends snugly against the inner wall of the cylinder 10 body.

The rotor B is driven rotarily in the cylinder by means of the shaft D which is secured thereto by being threaded into the stud H, the latter being held in vertical position by the collar I, which is tapered downwardly to fit the conical opening in the plate N, as aforesaid, whereby wear of the parts is taken up automatically. The collar serves the double purpose of securing the shaft D 15 and stud H in vertical position, and a slightly wedge shaped connection of said stud with the conical opening in the plate N, as above stated, and is the novel feature in connection therewith, to accomplish the object stated. The flat member C is a substitute for the two piston wings heretofore used by me, and automatically shifts through the transverse slot f in the rotor body with reciprocal action laterally, in such manner 20 that its marginal edges are constantly in slidable connection with the inner surface of the cylinder while being driven back and forth by the eccentric action of the rotor body, thereby causing a powerful suction 25 through the perforations O of the inner wall of the cylinder body on one side of the vertical rib or diaphragm M, and a like powerful draft outwardly and upwardly through the perforations O' on the opposite side of 30 said rib, with every revolution of said rotor. The vertical edges of the member C are preferably slotted to receive a thin wearing member d, which is kept in constant slidable connection with the inner wall of the cylinder body by the springs e e, shown in Fig. 3, while travelling thereon in the direction of 35 the arrow b through the elliptical space G around the rotor B.

The vertical rib or diaphragm M and the 40 spiral diaphragm L, which are stationary within the core K in the cylinder body A, unite at top and bottom thereof, and thus afford, in connection with the cored cavities

K K', improved means for suction and discharge (constituting a complete valve with 55 in said body), and more space for openings through the plates N N', for inflow and outflow of water, than would be otherwise possible, thus greatly increasing the capacity of the pump, and diminishing the power necessary to actuate the rotor B by the shaft D, as aforesaid.

Having thus fully described my invention, what I claim as new and desire to secure by Letters Patent is—

1. In a device of the character described, the combination with a cylindrical casing, of a piston rotor seated eccentrically therein, a wing slidably mounted in said rotor adapted to conform with the wall of said 70 conical well, while said rotor revolves; cavities within the wall of said casing, a vertical diaphragm dividing the cavities longitudinally; a spiral diaphragm in relation to said vertical diaphragm, dividing said cavities laterally; openings from said cavities inwardly on both sides of said vertical diaphragm; openings from and into said cavities above and below said spiral diaphragm, respectively, and means for actuating said 80 piston rotor, substantially as set forth.

2. In a device of the character described, the combination with a conical well, a conical rotor mounted eccentrically therein, a laterally shiftable wing loosely mounted 85 transversely in said rotor, cavities in the wall of the casing of said well, a vertical diaphragm, and a spiral diaphragm connected therewith, separating said cavities, openings leading into and from said cavities, 90 respectively, above and below the spiral diaphragm, openings inwardly from said cavities on both sides of said vertical diaphragm, means for automatically adjusting said rotor vertically, and means for connecting said 95 casing by threaded connections with adjacent pipe couplings above and below, substantially as set forth and for the purpose specified.

In witness whereof I hereunto set my hand 100 at Wooster, Ohio, this 24th day of December, A. D. 1920.

JOHN F. SMITH.
